UNITED STATES PATENT OFFICE.

DONALD T. HASTINGS, OF DETROIT, MICHIGAN, ASSIGNOR TO HOLLEY BROTHERS COMPANY, OF DETROIT, MICHIGAN, A CORPORATION OF MICHIGAN.

CARBURETER.

1,305,464.

Specification of Letters Patent. Patented June 3, 1919.

Application filed June 22, 1917. Serial No. 176,284.

To all whom it may concern:

Be it known that I, DONALD T. HASTINGS, a citizen of the United States of America, residing at Detroit, in the county of Wayne 5 and State of Michigan, have invented certain new and useful Improvements in Carbureters, of which the following is a specification, reference being had therein to the accompanying drawings.

10 The invention relates to carbureters of that type adapted to alternately use fuels of different grade, such for instance as gasoline and kerosene. With such constructions it is usual to start the engine with the more 15 volatile fuel and after a certain temperature condition is attained to shift to the less volatile fuel, the shifting being usually manually controlled. It is the object of the invention to provide automatic means 20 for shifting from one fuel to another and to this end the invention comprises the construction as hereinafter set forth.

In the drawings:

Figure 1 is a sectional elevation showing 25 a specific form of carbureter to which my improvement is applied;

Fig. 2 is a cross-section thereof;

Fig. 3 is a diagrammatic view illustrating the operation.

30 My improvement is applicable to various types of carbureter and in connection with various types of internal combustion engine, but as shown A is the inlet manifold of an internal combustion engine, B is the 35 exhaust manifold thereof and C is the carbureter. This carbureter comprises a Venturi tube D and a fuel inlet tube E therefor, which tube has a coiled portion F arranged in a chamber G connected with the exhaust 40 manifold B of the engine, whereby said coil is heated by the exhaust gases. H and H' are supply conduits for the different fuels which are connected to separate float chambers I and I' having float valves J and J' 45 therein. K is a fuel discharge nozzle in the conduit E which as shown surrounds an air inlet tube L. M is a supply passage for the nozzle K, and N is a valve for alternatively connecting said supply passage with 50 the float chambers I and I'. With the construction as described the variable suction produced by the Venturi tube D will draw air through the tube L and liquid fuel from

the nozzle K, the mixture being carried through the conduit E and heating coil F 55 therein, and being delivered into the venturi where it is commingled with additional air.

In starting the engine it is necessary to use a volatile fuel for the reason that the 60 coil F and adjacent parts are cold, under which condition it is impossible to form an explosive mixture with the less volatile fuel. On the other hand, after the engine is started and has been in operation for a sufficient 65 time to heat these parts the less volatile fuel may be used and will form a satisfactory explosive mixture. I have therefore provided automatic means for shifting from one fuel to another dependent upon temperature conditions, the construction shown 70 being as follows:

O is a thermostat which is arranged to be influenced by the temperature of the mixture passing through the inlet manifold, and 75 as shown is arranged in a pocket P connected with said manifold. The thermostat may be of any suitable type, but as shown is in the form of a longitudinally expansible chamber containing a volatile fluid, the boiling point of which determines the temperature 80 of operation. One end of the thermostat is anchored preferably adjustably by means of the swiveled screw Q and lock-nut Q', while the free end is connected by a 85 stem R to a rock arm S for operating the valve N. It is desirable to effect a quick operation of the valve in changing from one fuel to the other and to this end I have provided the following construction: The stem R is 90 connected to an alined stem R' through the medium of a lost-motion coupling T-T' and a spring T². The rock-arm S is also connected with a spring U which yieldably opposes its initial movement, but after a 95 certain angular movement operates to assist in the actuation of the valve. The tension of this spring U is also somewhat greater than the tension of the spring T². Thus in operation when the thermostat O 100 is first expanded it will compress the spring T² without movement of the stem R' or rock-arm S, but after a certain tension in the spring T² is acquired it will overcome the spring U, thereby effecting a quick or 105 snap movement which shifts the valve from

one position to the other. To limit the angular movement of the rock-arm S it is connected to the valve N by a step-up gearing V. However, the specific construction 5 of this mechanism is not essential, as any other means for obtaining the quick actuation of the valve will be equally effective.

What I claim as my invention is:

1. The combination with an internal combustion engine, of two containers for supplying fuels of different character to the engine, a valve having two positions in which the containers respectively have supply connection with the engine, mechanism for effecting a snap movement of said valve between said positions, and a thermostat influenced by the heat of the engine for controlling said mechanism.
2. The combination with an internal combustion engine, of two containers for supplying fuels of different character to the engine, a common supply means from said containers to the engine, a valve for alternatively opening said containers to said sup-

ply means, a thermostat influenced by the 25 heat of the engine, a spring variably stressed by said thermostat, a weaker spring resisting movement of said valve from either of its open positions, and mechanism actuatable by the stronger spring when the stress there- 30 of reaches a predetermined limit for shifting the valve in opposition to the weaker spring.

3. The combination with an internal combustion engine, of containers for supplying 35 fuels of different character to the engine, a common supply means from said containers to the engine, means for subjecting said supply means to the exhaust heat of the engine, a casing in communication with said supply 40 means, a thermostat in said casing, mechanism controlled by said thermostat for shifting said valve, a venturi in said supply means in advance of the thermostat, and means for admitting air to said supply 45 means in advance of said venturi.

In testimony whereof I affix my signature.
DONALD T. HASTINGS.
